REISSUED

UNITED STATES PATENT OFFICE.

CHARLES F. KURTZ, OF ROCK ISLAND, ILLINOIS.

DESIGN FOR A VENDING-MACHINE CASE.

Application filed July 25, 1927. Serial No. 22,867. Term of patent 3½ years.

To all whom it may concern:

Be it known that I, CHARLES F. KURTZ, a citizen of the United States, residing at Rock Island, in the county of Rock Island and State of Illinois, have invented a new, original, and ornamental Design for a Vending-Machine Case, of which the following is a specification, reference being had to the accompanying drawing, forming a part thereof.

In the drawings;

Fig. 1 is a front elevation of a vending machine case, embodying the new design.

Fig. 2 is a side elevation thereof.

What I claim, is;

The ornamental design for a vending machine case, as shown.

In testimony whereof I affix my signature.

CHARLES F. KURTZ.
